UNITED STATES PATENT OFFICE.

JAMES TROTTER, OF SYCAMORE, ILLINOIS, ASSIGNOR OF ONE-HALF TO
ALBERT J. HOPKINS, OF AURORA, ILLINOIS, AND JAMES BRENAN, OF
SYCAMORE, ILLINOIS.

LUBRICATOR.

No. 807,883.

Specification of Letters Patent.

Patented Dec. 19, 1905.

Application filed July 22, 1903. Serial No. 166,521.

To all whom it may concern:

Be it known that I, JAMES TROTTER, a citizen of the United States, residing at Sycamore, in the county of Dekalb and State of Illinois, have invented certain new and useful Improvements in Lubricators, of which the following is a full, clear, and exact specification.

My invention relates to force-feed lubricators, and more particularly to that type employed for delivering the lubricant to a chamber or other place containing steam or other pressure; and the invention has for its primary object to provide improved and efficient means for causing the lubricant to feed automatically, as desired, without the employment of pumps or other like forcing mechanism.

With these ends in view my invention consists in certain features of novelty in the construction, combination, and arrangement of parts by which the said objects and certain other objects hereinafter appearing are attained, all as fully described with reference to the accompanying drawings and more particularly pointed out in the claims.

In the said drawings, Figure 1 is a side elevation of my improved lubricator, partly in vertical section. Fig. 2 is a plan view thereof on a smaller scale, indicating diagrammatically a boiler and steam-chests to which the lubricant is supplied. Fig. 3 is an enlarged longitudinal sectional view of one of the automatic valves employed. Fig. 4 is a horizontal sectional view of a three-way valve employed for disconnecting the lubricator from either steam-chest, as desired; and Fig. 5 is a side elevation thereof.

In illustrating the purposes and an example of one of the uses to which my invention is applicable I have shown it in connection with a steam-boiler and the steam-chests of a steam-engine supplied by the boiler—such, for example, as a locomotive-boiler in connection with which two of such steam-chests are used—and consequently my lubricator is illustrated in duplex form, although it will, nevertheless, be understood that the invention is equally applicable to a single lubricator as well as to one comprising three or more feeds. Inasmuch as the employment of an additional feed simply involves the duplication of the feed-passages and controlling devices arranged therein, a description of one side of the lubricator or a single feed will suffice for a full understanding of the multiple form.

1 is a common form of sight-feed lubricator comprising a sight-feed or glass 2, with suitable fittings 3 4, connected together by the glass and upwardly through which and the glass the lubricant is allowed to feed as desired under the control of a feed-valve 5, as usual, one of the glasses 2 and its complement of fittings 3 4 and valve 5 being employed for each feed desired, two being shown in the drawings.

Assuming that the lubricator is to be applied to a steam-boiler employed for running a steam-engine and that the lubricant is to be fed into a steam-chest of the steam-engine or other place containing steam or other pressure, the fitting 4 will be connected by suitable passages to the steam-chest represented diagrammatically at 6 in Fig. 2, and the top of the lubricator 1 will be connected with the steam-boiler represented at 7 through suitable passages and controlling devices which will now be described.

The top of the lubricator 1 has direct connection by pipe or passage 8 with a diaphragm-chamber 9, which is divided into two compartments 10 11 by a flexible diaphragm or suitable abutment 12, carrying a valve 13, which normally closes a relief passage or vent 14, leading from the compartment 10. The compartment 10 also has direct connection through pipes or passages 15 16 with the boiler 7 or other source of pressure excepting when such connection is intercepted by a valve 17, held against its seat in a valve-housing 18 by boiler-pressure and also by means of a spring or other suitable cushion 19. The boiler-pipe 16 enters the valve-housing 18, as shown in Fig. 1, above the valve 17 and tends to seat the same, and the unseating is also resisted by the spring 19, which is coiled around stem 20 of the valve and bears upon a piston 21 or other suitable shoulder on the valve-stem. The piston 21 is arranged in cylinder 22, having an air-vent 23 to permit the piston 21 to move against the spring, and the lower end of this cylinder 22 is connected by a suitable passage to the steam-chests 6 or other place containing pressure wherein it is desired to deliver the lubricant, and if more than one of such chests be employed it is connected with all. Two being employed in the example shown in the drawings, each is provided with a feed-pipe 24, and these feed-pipes are connected to the cylinder 22 by a

cross-pipe 25 and branch 26 27, the part 27 of which is connected to the cross-pipe 25 by a fitting 28, in which may be located, if desired, a three-way valve 29, whereby either steam- 5 chest may be shut off from the lubricator if necessary. The passage 16 between the valve-housing 18 and the boiler may be under the control of a suitable valve 30, and ordinarily of course the connection between the steam-chests and the boiler would be under the control of a throttle or other suitable means, which is indicated at 31. It will thus be seen that when the valves 30 31 are open the action of the steam under the piston 21 will unseat 15 the valve 17 against the action of spring 19, and the steam direct from the boiler will pass into the upper part of lubricator 1 above the level of the lubricant therein. This pressure in the lubricator, however, is substantially 20 balanced or nearly balanced by the pressure coming from the steam-chest through the feed or delivery pipe 24 to the upper end of the glass 2 via fitting 4 and controlling devices, which I will now describe. The fitting 25 4 is connected by any suitable means 33 to a valve chamber or housing 32, in which is located a valve 34, intercepting communication between fitting 4 and delivery-pipe 24, which is also connected with the valve-housing 32, the valve 34 being arranged to close 30 against or toward steam-pressure coming from the chest through pipe 24. The valve 34 is provided with a stem 35, passing through a suitable stuffing-box 36 and thence into 35 a cylinder 37, in which is arranged a piston 38, connected in any suitable way to stem 35 and receiving pressure on one side from a spring 39, coiled around stem 35 and a sleeve 40, which constitutes a stop for limiting 40 the movement of the piston in one direction, and which piston receives pressure on the other side from the steam-chest 6 through a branch pipe 41, which is connected to cross-pipe 25 by a suitable connection 42, so that the pressure coming from the chest 6 45 tends to compress spring 39 and unseat valve 34, and thus open free passage between fitting 4 and pipe 24, whereby pressure may enter the bottom of lubricator 1 for counterbalancing 50 the pressure at the top of the lubricator and permitting the oil to feed through the pipe or passage 24 and its connections to the chest 6, the pressure above the oil or at the top of the lubricator being, if desired, sufficiently in excess of that at the bottom so that 55 the oil will be delivered by a force greater than that obtainable from mere gravity; but this preponderance of pressure should be automatically controlled and prevented from 60 becoming excessive, and thereby rushing the oil out of the lubricator too profusely. In order to accomplish this desirable end, the bottom compartment 11 of the diaphragm-chamber 9 is also connected by a pipe or passage 65 43 with the steam-chest, if desired, through

the intermediary of the branch 27 and a three-way fitting 44, connecting the branches 26, 27, and 43 together. Hence it will be seen that when the pressure in the upper compartment 10 of the diaphragm-chamber and on top of the lubricant equals the pressure coming from the steam-chest and that which is below the lubricant in the lubricator plus the resistance of the diaphragm 12 the lubricant will be fed by a force equal to the resistance of said diaphragm; but as soon as the pressure above the diaphragm and in the upper part of the lubricator exceeds the described force it will force the diaphragm 12 downwardly, and thereby open the vent 14, and consequently reduce the pressure in the upper part of the lubricator until the equilibrium is again established. In order, however, that the preponderance of pressure above the lubricant may not even momentarily feed the same too profusely into 85 the pipe 24, the valve 34 is closed as soon as such preponderance of pressure accumulates, and thereby prevents further feeding of the oil. Where the device is used in connection with steam-engines, however—such, for example, as locomotive-engines—the pressure in the steam-chest is continually fluctuating, and in order that the reduction of such pressure within certain bounds may not result in the closing of the valve 34 the piston 38 is 90 made of considerably larger area than said valve, so that the lower pressure of the steam-chest will be adequate to hold the valve 34 open against the action of the spring 39 and the pressure of the lubricant against the opposite face of valve 34, any slight variations in pressure above the lubricant that might result in excessive feeding being taken care of by automatic relief-valve 13.

45 is an emergency oiling-cup of the usual form communicating by passage 46 with the oil-delivery pipe 24 and having a screw-valve 47 for closing such communication when desired, 48 being a cap for such cup which is held in place by a spring 49, confined between said cap and a turning-knob 50 on the screw-valve 47.

Having thus described my invention, what I claim as new therein, and desire to secure by Letters Patent, is—

1. In a lubricator the combination with means for containing a supply of lubricant, a chamber containing fluid under pressure to be lubricated and a source of fluid-pressure, of a fluid-pressure regulator comprising two compartments having a movable abutment as a separator, a vent leading from one of said compartments and a valve for closing said vent operatively related to said abutment, means connecting said vented compartment with the said means for containing the supply of lubricant and also with said source of fluid-pressure, means connecting the other of said compartments with the chamber to be lubricated, and a lubricant feed or delivery

passage leading from said lubricant-supply to the chamber to be lubricated.

2. In a lubricator the combination with a receptacle for lubricant, a chamber containing a fluid under pressure to be lubricated, and a source of fluid under pressure, of a fluid-pressure regulator connected to both said source and receptacle and comprising means for reducing the pressure from said source in said receptacle, a valve interposed between said regulator and source, means for opening said valve by the pressure in the chamber to be lubricated and means for feeding the lubricant from said receptacle to the chamber to be lubricated.

3. In a lubricator the combination with a receptacle for lubricant, a chamber to be lubricated containing a fluid under pressure and a source of fluid-pressure, of a fluid-pressure regulator connected with said receptacle and source and comprising means for regulating the pressure in said receptacle coming from said source, a valve interposed between said pressure-regulator and source, means for opening said valve having connection with both said regulator and the chamber to be lubricated whereby the pressure in the chamber to be lubricated will open said valve and oppose the pressure from said source in said pressure-regulator, and means for conducting the lubricant from said receptacle to the chamber to be lubricated.

4. In a lubricator the combination with a receptacle for lubricant, a chamber to be lubricated containing fluid under pressure and a source of fluid under pressure, of a fluid-pressure regulator connected with said source and receptacle and comprising means for regulating the pressure in said receptacle coming from said source, a valve interposed between said regulator and source, a piston connected to said valve, a spring for holding said valve against its seat, a cylinder inclosing said piston and connected with said regulator and the chamber to be lubricated whereby the pressure from the chamber to be lubricated will act upon said piston and unseat said valve and will also operate said regulator, and means for conducting the lubricant from said receptacle to the chamber to be lubricated.

5. In a lubricator the combination with a receptacle for lubricant, a chamber to be lubricated containing fluid under pressure and a source of fluid under pressure, a connection between said source and receptacle, a pressure-regulator for controlling the pressure in

said receptacle coming from said source, a feed-outlet for the lubricant from said receptacle, a valve for opposing the flow of the lubricant therefrom, a fluid-pressure abutment connected with said valve for opening it and exposed to the pressure in the chamber to be lubricated for opening said valve thereby and means for conducting the lubricant to the chamber to be lubricated when said valve is opened.

6. In a lubricator the combination with a receptacle for lubricant having a feed-outlet, a chamber to be lubricated containing fluid under pressure and a source of fluid under pressure, of means connecting said receptacle and source, a fluid-pressure regulator interposed in said connection for regulating the pressure in said receptacle coming from said source, a valve for opposing the discharge of lubricant from said feed-outlet, a fluid-pressure abutment connected with said valve for opening it, means for exposing said abutment to the pressure in the chamber to be lubricated, means connecting said fluid-pressure regulator with the chamber to be lubricated for opposing the pressure in said regulator coming from said source and means for delivering the lubricant which passes said valve to the chamber to be lubricated.

7. In a lubricator the combination with a receptacle for lubricant having a feed-outlet, a chamber to be lubricated containing fluid under pressure, and a source of fluid under pressure, of a connection between said lubricant-receptacle and said source, a fluid-pressure regulator interposed in said connection for regulating the pressure in said receptacle coming from said source, a valve interposed in said connection between said source and said regulator, a fluid-pressure abutment for opening said valve, exposed to the pressure of the chamber to be lubricated, a lubricant-delivery passage between said outlet and chamber to be lubricated, a valve for closing said passage, a fluid-pressure abutment exposed to the pressure in the chamber to be lubricated for opening said second valve and a connection between said regulator and the chamber to be lubricated for opposing the pressure in the lubricator coming from said source by the pressure in the chamber to be lubricated.
